BY

Geo. P. Kiernan. ATTORNEY.

UNITED STATES PATENT OFFICE.

MARVIN E. RUTHERFORD, OF LOS ANGELES, CALIFORNIA.

STORAGE-BATTERY TERMINAL.

Application filed April 15, 1925. Serial No. 23,383.

This invention relates to the terminals of storage batteries, and has for one of its objects to simplify and improve the construction and increase the efficiency and utility of 5 devices of this character.

With these and other objects in view, the invention consists in certain novel features of construction as hereinafter shown and described and then specifically pointed out in 10 the claims, and in the drawings illustrative of the preferred embodiment of the invention—

Figure 1 is a vertical section of the improved device applied to a conventional 15 battery post.

Figure 2 is a perspective view from beneath, of the compressible coupling member.

Figure 3 is a perspective view, from beneath, of the conductor carrying sleeve. 20 The improved device comprises an internally and externally tapered inverted substantially cup-shaped member 10 constituting a male member closed at the smaller end as at 11, and preferably externally reduced at the smaller end as shown at 25

A threaded pin 13 extends from the smaller end of the tapered member, and the side walls of the latter are provided with a plurality of longitudinally directed clefts 30 14 cut entirely through the walls and opening through the larger end and terminating at the closed end, as shown.

One of the tapered battery posts is represented conventionally at 15, and the internal 35 taper of the member 10 corresponds to and is adapted to closely engage the post, as illustrated in Figure 1.

Bearing over the tapered tubular member 10 is an internally tapered inverted substantially cup-shaped coupling member 16 40 constituting a female member having a laterally extending socket 17 in which the conductor element, a portion of which is represented at 18, is soldered or otherwise 45 cured in the usual manner.

The member 16 is of greater length than the member 10, and is adapted to be firmly

clamped thereon by a flanged nut 19 which engages the threaded pin 13, as shown.

The space between the closed end 11 of the 50 tubular member and the flanged nut 19, and the space produced by the reduced portion 12 of the tubular member is designed to contain a lubricant, preferably hard grease, to lubricate the parts and prevent sulphuration, 55 the parts being of brass or the like.

While I have shown the improved device applied to one terminal post only, it will be understood that one of the improved devices will be applied to both the positive and 60 negative posts of each battery.

The improved device is simple in construction, can be inexpensively manufactured, and of any suitable material.

The preferred embodiment of the invention 65 is disclosed in the drawings and set forth in the specification, but it will be understood that modifications within the scope of the claimed invention may be made in the construction without departing from the 70 principle of the invention or sacrificing any of its advantages.

Having thus described my invention, what is claimed as new is:

A terminal of the character described, 75 comprising a pair of interfitting male and female members, each of substantially cup shape internally and externally tapered, the male member being longitudinally split at intervals and of greater length than the 80 female member, an external lateral nipple on the female member for the attachment thereto of a conductor, a central threaded lug on the top of the male member, the female member being provided with a central opening 85 in its top to receive the lug, and a nut engaged on the lug to work against the top of the female member, the slits in the male member being extended through the free edge and terminating at the top thereof. 90

In testimony whereof, I affix my signature hereto.

MARVIN E. RUTHERFORD.
